MODULATED CARRIER WAVE TRANSMITTER

William Stuart Leader Tringham, Surrey, England, assignor to Radio Corporation of America, a corporation of Delaware

Application November 16, 1934, Serial No. 753,291
In Great Britain November 17, 1933

7 Claims. (Cl. 179—171)

This invention relates to modulated carrier wave transmitters and apparatus for use therewith. More specifically the invention relates to what may be termed "modulation monitoring" arrangements for use in connection with radio and like transmitters and whereby the correctness of the modulation at different stages of the transmitter may be checked from time to time and during operation of the said transmitter.

10 According to this invention a modulation monitoring installation, for use for the purpose specified, comprises a cathode ray tube, means for deriving from a plurality of stages of the transmitter to be monitored, potentials which should be like functions of the degree of modulation, and switching means or its equivalent whereby any of the potentials so derived may be applied to deflect the ray in the cathode ray tube, the deflection of the ray thus obtained serving as an informative indication of the correctness or otherwise of operation of the transmitter.

15 Fig. 1 is a diagrammatic showing of the apparatus used in carrying the invention, and Fig. 2 is a modification thereof.

20 25 One method of carrying out the invention will now be described with reference to Figure 1 of the accompanying diagrammatic drawing said method relating to the primary intended application of the invention which is to amplitude modulation television transmitters of the kind wherein modulation is effected at the grid circuit of a high frequency amplifier stage.

In a practically convenient and satisfactory form of television transmitter, the said transmitter is modulated on the grid circuit of the penultimate high frequency stage, in such manner that the carrier current in the output circuit of that stage should be at any instant directly proportional to the instantaneous brightness of the picture to be transmitted.

Thus a certain predetermined low carrier output level corresponds to a black spot upon the picture and a high carrier level—namely the peak or maximum output which the transmitter can give practically without distortion—corresponds to a spot of maximum whiteness or brightness. In cases where the synchronizing signals are transmitted as modulations of the same carrier wave—the usual case—the said synchronizing signals may be transmitted, as is well known per se, by modulating the carrier to reduce the carrier level below the minimum value corresponding to black spots upon the picture.

In such a transmitter it is very desirable to be able from time to time to observe instantane-

ously the levels of modulation at different parts of the transmitter installation as a whole, and in particular it is very desirable to be able to compare wave shapes at (1) the input to the radio transmitter (2) the output of the modulated amplifier stage, and (3) the output of a power amplifier stage which usually succeeds the modulated amplifier stage.

In applying the present invention to provide a monitoring installation for use in connection with a transmitter as just described, there is provided a switch device SW having 12 contacts arranged in a circle, these contacts being numbered in the drawing in clockwise direction from 1 to 12. Contacts 1, 2 and 3 are connected together and earthed at E. Contacts 6, 7 and 8 are connected together and through a high frequency choke CH₁ to the gun or anode point to which is connected one deflecting plate of a cathode ray tube of ordinary oscilloscope type such as shown by Patent No. 1,592,274 to N. Kipping, issued July 13, 1926, and entitled Employment of cathode ray oscilloscopes. Contacts 9, 10 and 11 are also connected together and through a choke CH₂ to the deflecting plate terminal of the cathode ray tube. The ends of the chokes CH₁ CH₂ remote from the switch contacts are connected together through a resistance R, the ends of which in consequence constitute the input terminal IT of a cathode ray oscilloscope which is the indicating device for the whole installation. It is understood that the other pair of deflecting plates are connected to a sweep circuit as is illustrated in the above cited patent to Kipping. To avoid unwanted "pick up" of high frequency currents the choke CH₁ and CH₂ should be connected in circuit as close to the said oscilloscope as possible. The switch contacts are uniformly spaced as shown so that contact 1 is diametrically opposite contact 7 and contact 2 is diametrically opposite contact 8, and so on. The switch has two diametrically arranged rotatable bridge pieces A₁ and A₂ each of which can connect a desired pair of diametrically opposed contacts together. Switch contact 12 is connected to the positive terminal of a bias battery B and a movable tapping point T₁ thereon is connected to a movable tapping point T₂ upon a potentiometer resistance M which constitutes the modulation resistance in the grid circuit of the high frequency amplifier valves V₁ V₂ at which modulation is accomplished. Resistance M is earthed at one end and connected to the grid point of the parallel connected valves V₁ V₂ at the other. Switch contact 4 is connected through a

high frequency choke CH_3 to the electrical centre of a coil C_1 whose ends are connected to the anodes P_1 P_2 of a full wave rectifier D_1 having two anodes and a cathode K_1 , as in the usual way, the cathode being earthed. This coil C_1 is a coupling coil and is loosely coupled to the anode circuit of the power amplifier 21 following the stage V_1 V_2 at which modulation is effected i. e. the modulated amplifier stage. The remaining 10 switch contact 5 is similarly connected through a high frequency choke CH_4 to the electrical centre of a second coupling coil C_2 whose ends are connected to the anodes P_3 P_4 of a full wave rectifier D_2 having an earthed cathode K_2 . The coupling 15 coil C_2 is loosely coupled to the anode circuit of the high frequency amplifier V_1 V_2 at which modulation is effected. Filament heating currents for the two full wave rectifiers are taken through suitable resistances from the main low tension 20 supply for the transmitter as a whole.

The adjustments are made as follows:—

The coupling between the two coupling coils C_1 C_2 and their associated modulated carrier wave circuits are so adjusted that for a given carrier 25 level the same deflection in the cathode ray tube is produced whichever of the two full wave rectifiers is connected by the switch device to set up voltage at the input terminals IT of the cathode ray tube. The bias battery B and the tapping point T_2 are so adjusted that with the minimum amount of grid bias on the grid of the modulation stage V_1 V_2 which will give zero carrier level from the transmitter, the deflection of the cathode ray tube when its input terminals receive potential through contact 12 is zero and so that 30 with a given carrier level the deflection of the cathode ray tube is the same whichever of the three supplies is fed thereto by the switch, i. e. whether the input to the cathode ray tube is derived from contacts 12, 4 or 5. The two diametrical contact bridges A_1 A_2 of the switch are arranged to be rotated together by a single handle and to be at right angles to one another so that, for example, when contacts 6 and 12 are 35 bridged, contacts 3 and 9 are also bridged. It will be noted that with the arrangement described the sense of the voltages which are applicable to the cathode ray tube from the three different sources, is such that the deflection will always 40 be in the same direction.

The value of the resistance R across the input terminals of the cathode ray oscilloscope should be made sufficiently low to ensure that the capacity of the various inputs is negligible at all 45 modulation frequencies. If this be done the apparatus may be employed for frequency response measurements.

In the modification shown in Figure 2 the coupling between the anode circuit of the modulated amplifier stage V_1 V_2 and the grid circuit of the succeeding power amplifier stage (not shown) is effected through a concentric feeder OC , IC , whose outer tubular conductor OC is earthed. (Generally a similar method of coupling will be employed between the power amplifier and the transmitting aerial). With this method of coupling it is convenient to dispense with the coupling coils C_1 C_2 of Figure 1, and, 50 instead of employing inductive coupling to the rectifier D_1 D_2 , to take the modulated high frequency energy from the appropriate anode circuits via the concentric feeders connected thereto and suitable small condensers. The circuit 55 arrangement is shown in detail in Figure 2 for

the rectifier associated with the anode circuit of the stage V_1 V_2 . As will be seen this rectifier D_2 has an earthed cathode K_2 and has its anode P_3 connected through a choke CH_4 to the contact 5 and also through the coupling condensers F_1 F_2 to the inner conductor IC . The conductors IC , OC , are coupled through condensers F_3 F_4 and coil C_3 to the anode circuit of stage V_1 V_2 . The other rectifier D_1 has its cathode K_1 earthed and its anode P_1 connected through choke CH_3 to contact 4, said anode being also connected through coupling condensers F_1' , F_2' to the inner conductor of the tubular concentric feeder (not shown) associated with the anode circuit of the power amplifier stage (not shown). S_1 S_2 are screens. The use of coupling condensers for taking modulated high frequency energy from the concentric feeders is not necessary and other coupling expedients may be resorted to; for example, resistances may be used although such use is not preferred owing to the heating effects in resistance. Again, it is possible to use a combination of coupling condenser on the "live" side, following by a variable resistance. This arrangement is preferable to the use of coupling resistances simply, but there is little to choose between it and the use of coupling condensers as illustrated.

Preferably the oscilloscope used in carrying out this invention is mounted on or near the same control board or table as the main controls of the transmitter to be monitored or checked, in order that the said oscilloscope may be observed while operating the transmitter controls.

The oscilloscope can be used for measuring the "carry through" or degree of unbalance of high frequency energy when adjusting the neutralizing reactances of a neutralized high frequency valve amplifier employed in the transmitter. That is to say that if the amplifier is unbalanced as regards to neutralization, radio frequency energy will be passed through the grid to anode capacity and appear in the anode circuit of the amplifier tube even though no positive potential is connected to the anode. This radio frequency energy is known as the "carry through". The deflection of the ray will be an indication of the amount of "carry through"; further it can readily be ascertained what percentage of the normal carrier strength the "carry through" is.

Having now described my invention, what I claim is:

1. A modulation monitoring installation for use with a modulated radio transmitter wherein is provided a plurality of stages comprising a cathode ray tube oscilloscope, means for deriving from a plurality of stages of the transmitter to be monitored potentials which are predetermined functions of the degree of modulation and a single switching means whereby only one of the potentials so derived may be applied at any instant to deflect the ray in the cathode ray tube oscilloscope.

2. A modulation monitoring installation for use with a modulated radio transmitter wherein is provided a plurality of stages comprising a cathode ray tube oscilloscope, means for deriving modulated high frequency energy from a modulated amplifier stage of the transmitter to be monitored, means for rectifying said energy, means for deriving from a stage succeeding said modulated amplifier stage modulated high frequency energy, means for rectifying said last

mentioned energy, means for deriving from an impedance in the transmitter and wherein modulation energy flows, potentials corresponding to said modulation energy, and a single switching 5 means for applying at any instant only one of said mentioned potentials or either of the rectified outputs to the input terminals of a cathode ray oscilloscope.

3. A modulation monitoring installation for use 10 with a modulated radio transmitter wherein is provided a plurality of stages comprising a cathode ray tube oscilloscope, connections between one input terminal of said oscilloscope and three adjacent contacts of a rotary switch having 15 twelve equally spaced contacts arranged in a circle said switch also having two mutually perpendicular bridge arms adapted to be moved together each bridge arm being adapted to connect together diametrically opposite contacts of the 20 switch a connection between three further adjacent contacts of the switch and the other input terminal of the oscilloscope a connection between an impedance of the transmitter monitored, 25 through which modulation energy flows, and a seventh contact of the switch, a connection between an eighth contact of the switch and a rectifier connected and arranged to rectify modulated high frequency energy derived from the anode circuit of a modulated amplifier in said transmitter, 30 a connection between a ninth contact of the

switch and a rectifier connected and arranged to modify modulated high frequency energy derived from the anode circuit of a stage succeeding said modulated amplifier stage, the remaining three switch contacts being connected together and earthed, the whole arrangement being such that by rotating the two bridge arms together to different positions either voltages from the modulation impedance or voltages from either of the rectifiers may be applied to deflect the ray within the 10 cathode ray tube.

4. An installation as claimed in claim 3 and wherein the rectifiers are energized through inductive coupling circuits are of the full wave type.

5. An installation as claimed in claim 3 and 15 wherein the rectifiers are energized through capacitative coupling means connected to concentric feeder coupling devices in the transmitter.

6. An installation as claimed in claim 3 and 20 comprising chokes inserted in the leads to the input terminals of the cathode ray tube oscilloscope said chokes being adjacent said terminals.

7. An installation as claimed in claim 3, and 25 wherein connection between the modulation impedance and the associated contact of the switch is made via an adjustable tapping point so that the magnitude of the modulation potentials applied to the oscilloscope may be adjusted.
